[57] CLAIM

The ornamental design for an environmentally sealed electrical terminal with hook-up wire management, as shown and described.

DESCRIPTION

FIG. 1 is a slightly enlarged isometric rear view of top and bottom portions of an environmentally sealed protection terminal having hook-up wire management, according to the principles of the present invention;

FIG. 2 is a slightly enlarged isometric front view of the apparatus as disclosed in FIG. 1;

FIG. 3 is a slightly enlarged isometric rear view of the bottom portion of the environmentally sealed protection terminal with the top portion removed;

FIG. 4 is a slightly enlarged isometric front view of the bottom portion of the apparatus shown in FIG. 3 with the top portion removed;

FIG. 5 is a front view in elevation of the environmentally sealed protection apparatus shown in FIG. 1;

FIG. 6 is rear view in elevation of the apparatus shown in FIG. 5;

FIG. 7 is side view in elevation of the apparatus shown in FIG. 5;

FIG. 8 is an opposite side view in elevation of the apparatus shown in FIG. 5;

FIG. 9 is top plan view of the apparatus shown in FIG. 5; and,

FIG. 10 is bottom plan view of the apparatus shown in FIG. 5.
